A technical drawing of a mechanical part, likely a lever or handle. The part is elongated with a slot in the center. A circular area within the slot is hatched with diagonal lines. The number '10' is printed next to this hatched circle. The drawing is signed 'Young, Young' in cursive script at the top right, and 'C. Horneys' in a similar script at the bottom right.

UNITED STATES PATENT OFFICE.

EDWARD E. NELDNER, OF MILWAUKEE, WISCONSIN.

INTERNAL-COMBUSTION ENGINE.

Application filed July 15, 1922. Serial No. 575,360.

To all whom it may concern:

Be it known that I, EDWARD E. NELDNER, a citizen of the United States, and resident of Milwaukee, in the county of Milwaukee and State of Wisconsin, have invented certain new and useful Improvements in Internal-Combustion Engines; and I do hereby declare that the following is a full, clear, and exact description thereof.

10 My invention relates to a new and useful improvement in connection with internal combustion engines, and more particularly to the mechanism by means of which the reciprocating motion of the pistons is transmitted and converted into the rotary motion of the power shaft.

In engines of the more common type, wherein the piston rod is connected directly to the crank shaft, the piston rod is comparatively short with respect to the throw of the crank shaft and the resulting side thrust on the piston results in excessive and unequal wear on the same, thus materially lessening the life of the engine.

25 It is the primary object of my invention to construct a practical and efficient engine wherein the impulses of the pistons are transmitted through the piston rod in a comparatively straight line to the ends of a walking beam which carries a yoke which has a slot receiving the wrist pin and transmitting motion through the same to the power shaft.

A more specific object of the invention is 35 to provide improved means for guiding the wrist pin in the yoke, whereby excessive wear on the latter will be effectively prevented.

With the above and other objects in view, 40 which will be apparent from the following description, the invention consists in certain structural details which will be specifically described in connection with the accompanying drawings, and subsequently claimed.

45 In the drawings,

Figure 1 is a vertical longitudinal view of my invention partly in section and partly in elevation.

50 Figure 2 is a view similar to Figure 1 but on a plane at right angles thereto.

Figures 3 and 4 are detailed views of parts of the invention.

Referring more specifically to the drawings, the device comprises a casing 5 having 55 bearings 6 in which is journalled the power shaft 7. A combined fly-wheel and crank

disk 8 is secured to the power shaft, and is driven by means, hereinafter described, from one or more walking beams 9, which, in turn, derive their power from the cylinders of the engine.

In the preferred embodiment, which is illustrated in the drawings, there are two walking beams and four cylinders, but it will be obvious that the number may be varied. Each of the walking beams is secured to a sleeve 10 which is journalled on a shaft 11 and each end of the walking beam is pivotally connected to a piston rod 12 which is connected with a head 13 reciprocably mounted in a cylinder 14.

Secured to the sleeve 10 is a yoke 15, which is provided with an arcuate slot 16, described about the center of the shaft 11, and providing a path for the shaft 7 as the yoke 15 is oscillated about its axis. A wrist pin 17 is journalled in the wheel 8, and is provided with a head consisting of two branches 18 and 19 having oppositely disposed flat faces, which are guided in the slot 20 which extends radially of the yoke and intersects the slot 16 at right angles.

It will be understood that as the explosions take place successively in the different cylinders, the walking beams and yokes will be oscillated about their axes, and the wrist pin 17 will be revolved thereby about the shaft 7. During this movement, the wrist pin head will travel from the position shown in Figure 2 downwardly in the slot 20, and across the slot 16. In the absence of any guiding means, it has been found that the edges of the wrist pin head are liable to deviate from a straight line in crossing the slot 16, and this results in a knocking and 90 wearing on the corners where the slots intersect.

For the purpose of guiding the wrist pin head, therefore, I have provided a pair of flat blocks 21 and 22 embracing the shaft 7 and held in the slot 16 by means of a pair of symmetrical arms 23 and 24 which are journalled on the shaft 11 by means of a split bearing 25, and are resiliently held together by means of the spring devices 26. 100 In passing, therefore, from the position shown in Figure 2 to the position shown in Figure 3, the wrist pin head will straddle the block 21, the head being cut away at 27 to permit the ready engagement therewith 110 as the wrist pin continues to travel in its circular path about the shaft 7, its head will

ride across the slot 16, being guided by the block 21 which is forced outwardly from the shaft 7 in opposition to the spring device 26. In completing its revolution, the wrist pin 5 will pass upwardly on the other side of the shaft 7 and will be guided across the slot by the guide 22, the opposite corner of the head being cut away, as shown at 28, to permit the ready engagement with the block.

10 It will be seen that in the operation of my improved engine, the ends of the walking beams will travel in comparatively short arcs which are tangential to the axes of the cylinders. The angular movement of the 15 piston rods therefore, is very small, and there will be very little side thrust against the cylinders. The slight wear which does occur, will be distributed uniformly about the pistons and cylinders.

20 It will also be seen that the wrist pin head will be accurately guided in the slot 20, and there will be no excessive wear at the corners between the slots.

While I have shown and described what 25 is at present the preferred embodiment of my invention, it will be understood that various modifications may be made in the structural details thereof without departing from its scope, as claimed.

30 I claim:

1. In a device of the character described, a rotatable shaft having a drive member secured thereto, a wrist pin carried by the drive member, a walking beam mounted on 35 an axis parallel to said shaft and having a yoke provided with an arcuate slot in which said shaft rides when the walking beam is oscillated, and a radial slot in which said wrist pin is guided about the shaft, and a 40 pair of pistons operable to oscillate said beam.

2. In a device of the character described, a rotatable shaft having a drive member secured thereto, a wrist-pin journalled in the 45 drive member and having a head with oppositely disposed flat faces, a walking beam

mounted to rock about an axis parallel to said shaft, a yoke secured to the beam and having a radial slot for receiving and guiding the wrist pin head as it revolves about said shaft, an arcuate slot intersecting said radial slot and receiving said shaft, means for rocking said beam and yoke, and flat yieldably held blocks for engaging the flat faces of the wrist pin head to guide the same 55 across said arcuate slot.

3. In a device of the character described, a rotatable shaft having a drive member secured thereto, a wrist-pin mounted in the drive member, a yoke mounted for oscillation about an axis parallel to said shaft, a driving connection between the yoke and wrist-pin including a radially disposed slot in said yoke which receives the wrist-pin to guide the same in its revolution about the 60 shaft, said yoke having also an arcuate slot intersecting the radial slot at right angles and through which the shaft extends, means for guiding the wrist-pin as it moves across the arcuate slot to prevent the same from 65 striking the corners at the intersection of the slots.

4. In a device of the character described, a rotatable shaft having a drive member secured thereto, a wrist-pin journalled in the 70 drive member and having a head with oppositely disposed flat faces, means for rotating the drive member including an oscillating yoke having a radial slot receiving said wrist-pin head and an arcuate slot intersecting said radial slot and through which the shaft extends, and a pair of flat blocks in 75 said arcuate slot embracing said shaft and held resiliently against the same, said blocks 80 being engageable by the wrist-pin head to 85 guide the latter as it travels across the arcuate slot.

In testimony that I claim the foregoing I have hereunto set my hand at Milwaukee, in the county of Milwaukee and State of 90 Wisconsin.

EDWARD E. NELDNER.
